ABSTRACT: A pin carriage return mechanism is disclosed in which the pin carriage is returned from an advanced position to its initial home position by a flexible cord. The latter is attached at one end of the pin carriage and is anchored at its opposite end. An intermediate part of the cord is looped over a roller, which is orbited about a fixed center during each cycle of the machine to return the cord and pin carriage.

PIN CARRIAGE RETURN MECHANISM

This invention relates to business machines, such as adding and calculating machines, and has particular reference to machines of the 10-key type.

Machines of the above type utilize stop pin carriages having coordinate columns and rows of stop pins therein settable to actuator-arresting positions. Upon depression of a numeral key, a pin in a row of the pin carriage corresponding in value to the value of the depressed key is set and the carriage is yieldably advanced one columnar distance or one denominational order. After the whole amount is set up in the stop pins, the machine is cycled, causing the actuators to be advanced until differentially arrested by set ones of the stop pins. The pin carriage is then returned to its initial home position preparatory to setting up a new account.

Due to the relatively large mass of the pin carriage and the distance it must traverse in returning to its home position, and further, due to the short time in which it must be returned, the pin carriage return or restore operation tends to create considerable noise and jarring action. An additional factor which aggravates this condition is that the pin carriage may be advanced to any of its different columnar positions in setting up of amounts of different capacities and thus the carriage return mechanism must pick up the carriage in any of such positions.

It therefore becomes the principle object of the present invention to provide a novel pin carriage return mechanism which is relatively smooth and quiet in operation.

Another object is to provide a pin carriage return mechanism which is simple and economical to manufacture.

Another object is to provide a pin carriage return mechanism which reduces the amount of shock and jarring normally found in such a mechanism.

A further object is to provide a pin carriage return mechanism which requires a minimum amount of space in the machine.

The invention incorporates a cord attached at one end to the pin carriage and activated by a drive element movable in an orbit about a fixed center to impart a harmonically accelerated motion to the cord. Because the cord has an appreciable length and is guided in different directions by stationary guide elements a light snubbing action occurs causing it to pick up the pin carriage in a relatively smooth and quiet manner, rather than abruptly, regardless of the columnar position the pin carriage happens to be in. This is enhanced by using a cord of plastic or similar flexible material. Also, because of the harmonically accelerated motion imparted to the cord by the orbiting drive element, the carriage is returned rapidly and smoothly to its home position.

The manner in which the above and other objects of the invention are accomplished will be readily understood on reference to the following specification when read in conjunction with the accompanying drawings, wherein:

FIG. 1 is a plan view, partly broken away, illustrating the key board and part of the pin carriage of an adding-listing machine and embodying a preferred form of the invention.

FIG. 2 is a longitudinal sectional view through a portion of the machine.

FIG. 3 is a sectional view illustrating the orbiting cord drive device.

FIG. 4 is a transverse sectional view taken along line 4-4 of FIG. 3.

FIG. 5 is a sectional plan view taken substantial on line 5-5 of FIG. 2.

FIG. 6 is a sectional view through the printing sector assembly and is taken on line 6-6 of FIG. 2.

FIG. 7 is a transverse sectional view illustrating the cyclic drive clutch.

FIG. 8 is a sectional view illustrating a modified form of the invention embodying a repeat key.

FIG. 9 is a sectional view taken along line 9-9 of FIG. 8.

Referring to the drawings, the machine in which the embodiment of the invention is disclosed is the commercially available Addmaster adding machine which is disclosed basically in the R. E. Busch U.S. Pat. No. 3,113,719, issued on

Dec. 10, 1963, the H. L. Clary et al. U.S. Pat. No. 3,132,582, issued on May 12, 1964, and the J. G. Clary U.S. Pat. application, Ser. No. 723,777, filed Apr. 2, 1968, now U.S. Pat. No. 3,481,536.

5 The machine is motor driven through a cyclically operable clutch 11, FIG. 7, and is controlled by a key board, including 10 amount keys, generally indicated at 12, an add-subtotal bar 13, and a subtract-total bar 14.

An arcuate stop pin carriage 15 carrying a plurality of settable stop pins 16 is guided for movement transversely of the machine by a guide rod 17 adjacent to the lower end thereof and by a channel-shaped guide member 18 adjacent its upper end. An arm 20, extending upwardly from the pin carriage frame, is guided along a slot in the member 18 and terminates in knob 21 which extends through a slot 22 in a machine cover 23, permitting the pin carriage to be manually returned to the right to its illustrated home position.

The stop pins 16 are arranged in a plurality of horizontally extending rows and a plurality of vertically extending columns, there being 10 such pins in each column ranging in value from zero to nine.

Each of the amount keys 12 is slideably supported for vertical movement and is connected to a respective flexible cable 24 guided for endwise movement in a guide block 25 suitably secured below the key board. All of the cables 24 are located in a vertical plane which lies coincident with the left-hand column of stop pins 16 when the pin carriage is in its right-hand or home position shown in FIGS. 1 and 5. When an amount key is depressed its cable moves the aligned stop pin 16 from its illustrated unset position to a set position.

The upper row of pins 16a, when set, enable incremental or columnar escapement of the pin carriage to the left as an incident to depression of each of the amount keys, and for this purpose the leftmost upper pin 16a normally rests against a fixed stop 26. When any amount key is depressed, it operates through its respective cable 24 to set an aligned stop pin 16 and at the same time it activates a universal plate 27 which cooperates with a bail 28 to set the aligned escapement pin 16a.

When the leftmost escapement pin 16a is set, a tension spring 30 extending between the pin carriage and a machine side frame plate 31 advances the pin carriage leftward to align the leftmost column of stop pins 16 with a right-hand printing sector 32. As other amount keys are depressed, the pin carriage is further advanced to the left to align addition columns of stop pins with other denominational arrangements 32.

The sectors 32 are independently pivoted on a support shaft 33. Each sector has a shoulder 34 adapted to limit against a set one of the pins 16 during clockwise rocking of the sectors as will be described presently. Each sector also carries a font of type characters 35 ranging in value from zero to nine. Such type characters coact with printing hammers 36 to record amounts on a paper strip 37 which is fed between the sectors and the hammers.

Gear teeth 38 on the sectors are arranged to mesh with and drive a suitable accumulator partly indicated at 40.

Upon entry of an amount in the pins 16 of the pin carriage, the machine is operated to add or subtract such amount to or from the accumulator 40 by depressing either the add-subtotal bar 13 or the subtract-total bar 14. Such bars when depressed release a clutch control member partly indicated at 41, FIG. 7, from engagement with a clutch dog 42, forming part of the cyclic clutch 11. Accordingly, the clutch dog, which is carried by a clutch disc 43 attached to a camshaft 44, clutches a motor-driven ratchet wheel 45 to rotate the shaft one complete revolution.

The shaft 44 carries a cam 46, FIG. 2, which cooperates with a combined cam follower and gear sector 47 fulcrummed at 48 to oscillate a gear sector 50 mounted on shaft 33. The sector and a similar member (not shown) on the opposite side of the machine support a bail rod 51 which extends through openings 52 in the various sectors 32 and engages spring tails 53 formed integrally with the sectors. Thus, during each cycle

of the machine, the sectors are advanced clockwise until their shoulders 34 limit against set ones of the stop pins 16 thus presenting appropriate type characters 35 to be imprinted against the paper strip 37 by the hammers 36. For this purpose, a suitable printing ribbon 39 is suitably supported below the paper strip.

After the sectors 32 have been differentially advanced, and before the hammers 36 are operated to print an amount, cam formations 54 on the sector 50 and on its counterpart on the opposite side of the machine cam aligner bar 55 upwardly along guide slots 56 in machine side support plates, i.e. 57, to engage between detent teeth 58 formed in the sectors so as to accurately align the type characters relative to the hammers.

According to the present invention, the pin carriage is returned to its illustrated home position by a flexible cord 60, FIGS. 3, 4 and 5 preferably formed of woven plastic, such as is available under the trademark Nylon, or similar relatively flexible material. Such cord is attached at 61 to a part of the pin carriage 15 and is guided in a relatively small radius through a plastic guide grommet 62 secured to a bottom frame plate 63 of the machine. The cord is guided across the machine, through a second guide grommet 64 and into a loop 74 extending around an eccentrically mounted roller 65 from which it is returned through the grommet 64 and is anchored by a suitable clamp 66 to the bottom plate 63.

The roller 65 is rotatably mounted on a stud 66 formed integral with a disc 67. A second disc 68 is integrally secured to the stud 66 and is spaced from the disc 67 a distance substantially equal to the cross-sectional diameter of the cord which, in this case, is on the order of 0.050 inch. The disc 67 is freely rotatable on the left-hand end (FIG. 3) of the shaft 44 and a pair of ledges 70 extend radially along the right-hand face of the disc. Such ledges are located in the path of a projection 71 formed integral with a member 72 which is suitably secured to the shaft 44.

Normally, when the pin carriage is in its illustrated home position, the excess portion of the cord is contained in a loop 74 which is held by light frictional engagement between the two discs 67 and 68, thereby preventing it from hanging loosely in other parts of the machine where it could possibly catch on different operating parts. However, as the pin carriage is stepped to the left across the machine in entering amounts therein, the loop closes up and, if an amount equal to the full capacity of the pin carriage is entered, the loop closes around the roller 65 as indicated by the dot-dash lines 74a. When the machine is at its full cycle, or rest position, as shown, the projection 71 is located approximately 180° from the adjacent ledge 70.

Now, during the early part of a machine cycle, while the printing sectors 32 are being differentially advanced in a clockwise direction by the bail 51, shaft 44 carries the member 72 and its projection 71 clockwise as seen in FIG. 4. At approximately midcycle, and after the printing operation has occurred, the projection 71 engages the adjacent ledge 70 to rotate the discs 67 and 68 so as to orbit the roller 65. The roller 65 thus enlarges the loop 74, drawing the pin carriage rightward toward and slightly past its home position to an extreme right-hand position where it strikes a resilient bumper 69, FIG. 1. At this point the roller 65 reaches a position indicated by the dot-dash line 65a in which position it has moved past dead center relative to the direction of force exerted by it against the loop. Thus, as the pin carriage rebounds leftwardly from its extreme right-hand position to its home position, the cord further advances the discs 67 and 68 and they assume, or tend to assume, their positions shown as FIGS. 3 and 4, particularly by virtue of the weight of the stud 66 and roller 65.

FIGS. 8 and 9 illustrate a modified form of the invention in which a depressible repeat key 80 is provided which is effective upon depression to cause repeated entries of amounts initially set in the pin carriage. Key 80 is guided by slots 81 and 82 formed in a key guide plate 83 and in the side frame plate 31, respectively, and is normally held in its illustrated raised

position by a tension spring 84. The stem of key 80 carries a stud 85 which normally lies in latching engagement with one leg of a bail 86 pivotally supported at 87. The bail 86 carries a pulley 90 around which the aforementioned cord 60 is looped. The cord, in this case, extends from the aforementioned guide grommet 64, FIG. 5, and is anchored at 91 on the side frame 31. A light tension spring 88 normally urges the bail 86 into its illustrated position where it rests against a frame stud 89.

When the repeat 80 key is not depressed, the portion of the cord shown in FIG. 9 remains immovable and the pin carriage is accordingly returned to its home position during the later half of the machine cycle, as was described heretofore. However, upon depression of the repeat key an ear 92 on the stem thereof activates a lever partly shown at 93 which, through linkage (not shown), moves the clutch control member 41 to cause engagement of clutch 11, and cycling of the machine. Also, at this time, the stud 85 passes from latching engagement with the bail 86 and since the spring 88 is weaker than spring 30, such spring will yield, enabling the cord 60 to rock the bail 86 counterclockwise, thereby leaving the pin carriage in its advanced position, as long as the repeat key is held depressed. During the later portion of each machine cycle the bail 86 is returned counterclockwise by its spring 88 and if the repeat key 80 is released from depression the stud 85 will return to latching engagement with the bail.

I claim:

1. In a cyclically operable calculating machine having a stop pin carriage,
spring means for advancing said carriage from a home position,
mechanism for returning said carriage to said home position from any advanced position comprising,
a cable,
means connecting said cable adjacent one end thereof to said pin carriage,
means including a drive member operatively connected to said cable adjacent the opposite end of said cable;
means supporting said drive member for orbiting movement about a center,
an actuating member moveable through a complete revolution during each cycle of said machine, and
means forming a lost-motion connection between said actuating member and said drive member whereby said actuating member is effective to drive said drive member through a portion of a revolution and said spring means is effective to cause said cable to drive said drive member through another portion of said last-mentioned revolution independently of said actuating member.

2. Mechanism according to claim 1 comprising means anchoring said cable adjacent said opposite end thereof, said drive member engaging an intermediate part of said cable.

3. Mechanism according to claim 2 wherein said supporting means form a pair of facing surfaces extending normal to the axis of said drive member,

said surfaces being spaced apart a distance substantially equal to the diameter of said cable whereby to retain any surplus length of cable therebetween by friction.

4. Mechanism according to claim 2 comprising means for guiding said cable to and from said drive member in a loop.

5. Mechanism according to claim 2 comprising means for guiding said cable to and from said drive member in a loop, said actuating member being effective to drive said drive member past dead center relative to said loop, and

said spring means being effective to cause said cable to advance said drive member relative to said actuating member after said drive member moves past dead center.

6. Mechanism according to claim 2 comprising a depressible repeat key, and

means controlled by said key upon depression thereof for releasing said anchoring means.

7. In a cyclically operable calculating machine having a stop pin carriage,
spring means for advancing said carriage from a home position,

mechanisms for returning said carriage to said home position comprising,
 a cable,
 means connecting said cable adjacent one end thereof to
 said pin carriage,
 means for anchoring said cable adjacent the opposite end
 thereof,
 a cable drive member,
 means rotatably supporting said drive member for orbiting
 movement about a center,
 an actuating member moveable through a complete revolution
 during each cycle of said machine,
 means forming a lost-motion connection between said ac-
 tuating member and said drive member whereby said ac-
 tuating member is effective to drive said drive member
 through a portion of a revolution and said spring means is
 effective to cause said cable to drive said drive member
 through another portion of said last mentioned revolution,
 means for guiding an intermediate portion of said cable in a 20
 loop to and from said drive member, and
 means forming a pair of spaced guide surfaces between
 which said cable is moved,
 said guide surfaces frictionally engaging said cable whereby
 to retain any surplus length of said cable therebetween.
 8. In a cyclically operable calculating machine having a stop
 pin carriage,
 first spring means for advancing said carriage from a home
 position,
 mechanism for returning said carriage to said home position 30
 from any advanced position comprising,
 a cable,
 means connecting said cable adjacent one end thereof to

said pin carriage,
 a second spring means for anchoring said cable adjacent to
 the opposite end thereof,
 said first spring means being adapted to overcome said
 second spring means,
 a cable drive member engageable with said cable,
 means supporting said drive member for orbiting movement
 about a center,
 an actuating member moveable through a complete revolution
 during each cycle of said machine,
 means forming a lost motion connection between said ac-
 tuating member and said drive member,
 means normally blocking said second spring means from
 yielding,
 a compressible repeat key,
 and means controlled by said key upon depression thereof
 for releasing said blocking means,
 said drive means being ineffective to cause said cable to
 return said carriage upon yielding of said second spring.
 9. Mechanism according to claim 7 wherein said guide sur-
 faces frictionally engage at least a portion of said cable ex-
 tending in said loop.
 10. Mechanism according to claim 2 wherein said support-
 ing means comprises a pair of spaced rotatable cable guide
 members,
 means for guiding said cable in a loop to and from said drive
 member,
 said loop passing between said guide members,
 and said guide members frictionally engaging said cable
 whereby to retain any surplus length of said cable
 therebetween.
